EMBALMER'S PROTECTOR

Edward R. Moore, Fargo, N. Dak.

Application September 20, 1946, Serial No. 698,309

5 Claims. (Cl. 27—21)

1

This invention relates to undertaking apparatus and, more particularly, to an embalmer's protector.

The primary object of the invention is to provide an embalmer's protector adapted to be placed over a corpse for covering the torso, but yet providing access locally to the femoral vein. It is further intended to provide a protector which may be stretched across the torso of the subject and easily hooked at both ends to the edge of an embalmer's table, not only to cover over vital parts of the deceased, but also providing a depending flap-like shield, thereby assuring the maximum permissible privacy during the necessary injection of fluid into the femoral vein. In addition, it is intended to provide an easily cleanable shield for protecting the parts of the body adjacent the region of access to the femoral vein from any fluids which might escape during the injection.

These and other objects will be apparent from the following specification and drawings in which, Fig. 1 is a plan view of the protector; and,

Fig. 2 is a side elevation.

Referring now to the drawing, in which like reference numerals denote similar elements, the shield 2 is generally in the shape of an elongated rectangle, preferably of a flexible, waterproof, and easily-cleanable material or fabric such as oiled silk. While overall size is not critical, a strip 3 of oiled silk approximately twenty-four inches long and about eleven inches wide has been found adequate. Preferably, the edges of strip 3 are finished, as indicated at 4.

At each end of strip 3 there are attached a pair of elastic straps 6, the inner ends 8 of which are securely stitched to the ends of the strips, the outer ends having attached thereon hooks 10. One side of strip 3 is provided with an opening 12, and the assembly is completed by a flap 14, also of some flexible material such as oiled silk, the flap being centrally secured to one edge of strip 3 as by stitches 16 although it is apparent that it may be cut integrally with the strip if desired.

In the use of this device, the hooks 10 at one end of the assembly are hooked beneath one edge of the embalmer's table, strip 3 is stretched across the lower regions of the corpse in such manner that opening 12 is at the region of the femoral artery to which access is desired, and the other hooks 10 are hooked beneath edge of the table on the other side. In this position, flap 14 and strip 3 provide certain privacy and protection for the subject.

The invention, while detailed in connection with a successfully proved embodiment, is not to be limited to the specific construction illustrated, but is intended to cover all equivalent arrange-

ments within the circumscription of the following claims:

I claim:

1. An embalmer's protector comprising a strip of flexible material adapted to overlie the lower regions of a subject corpse, means at opposite ends of said strip for attachment to the sides of an embalmer's table, and eccentric aperture means through said strip for providing direct access to the region of the femoral vein.

2. An embalmer's protector comprising an elongated strip of flexible material adapted to overlie transversely the lower regions of a subject corpse, means at the ends of said strip for attachment to the sides of an embalmer's table, a flap centrally secured to one side edge of said strip for insuring privacy to the subject, and eccentric aperture means through said strip for providing direct access to the region of the femoral vein.

3. An embalmer's protector comprising an elongated strip of flexible material adapted to overlie transversely the lower regions of a subject corpse, a pair of spaced elastic straps secured to and extending outwardly from each end of said strip, means on the ends of said straps for securement to the sides of an embalmer's table, and aperture means through said strip disposed between the middle and one side edge thereof for providing direct access to the region of the subject's femoral vein.

4. The combination claimed in claim 3, and a relatively small flap of flexible material centrally secured to one side edge of said strip.

5. An embalmer's protector comprising an elongated strip of flexible material adapted to overlie transversely the lower regions of a subject corpse, a pair of spaced elastic straps secured to and extending outwardly from each end of said strip, hooks on the free ends of said straps for engagement beneath the side edges of an embalmer's table, said strip having an aperture therethrough disposed between the middle and one end edge thereof for providing direct access to the region of the subject's femoral vein, and a flap of flexible material extending outwardly from the central portion of one side edge of said strip for insuring privacy to the subject.
